United States Patent Office.

DAVID VOGT, OF TRENTON, MICHIGAN.

Letters Patent No. 103,945, dated June 7, 1870.

IMPROVED WASHING-MACHINE.

The Schedule referred to in these Letters Patent and making part of the same

To whom it may concern:

Be it known that I, DAVID VOGT, of Trenton, in the county of Wayne and State of Michigan, have invented a new and useful Improvement in Washing-Machines; and I do declare that the following is a true and accurate description thereof, reference being had to the accompanying drawing, and to the letters of reference marked thereon, and being a part of this specification.

The drawing shows my invention in perspective, with parts broken away to more fully show its construction and operation.

The nature of this invention relates to an improvement in washing-machines, and consists in the peculiar construction and arrangement, on a frame, of a tub, in which is secured a longitudinal rub-board, and in peculiar construction and arrangement of a reciprocating and oscillating rubber, operated by a treadle, the fabric to be cleansed being subjected to a rolling pressure between the rub-board and rubber, as when being washed by hand, the laundress having both hands free to manipulate the fabrics.

In the drawing—

A represents a frame, on which is secured a wash-tub, B. The front standards of the frame are carried up above the table on which the tub rests.

In the lower part of these standards a cranked shaft, C, is journaled, to which motion is communicated through a treadle, D, whose fulcrum is a rock-shaft, E, journaled in the side rails A' of the frame, the rear ends of these rails terminating in handles d.

F is a fly-wheel on the shaft C. It also serves to convert the device into a barrow for moving the same about, the handles d serving as barrow-handles.

G is a pulley on the shaft C, from which motion is

communicated to a cranked shaft, H, through a belt, I, passing over its pulley J, from that on the shaft C, the shaft H being journaled above the table.

K is a corrugated rub-board, longitudinally secured in the tub B, and

L is a corrugated rubber resting thereon, reciprocated by a pitman, M, pivoted thereto, and strapped to the crank of the shaft H.

A yoke, N, straddles the pitman, and to the ends of its forks the front end of the rubber is suspended, whereby, in its reciprocation, it is also oscillated.

The fabrics to be cleansed being immersed in the hot suds contained in the tub, the laundress introduces a garment between the rubber and rub-board, and, working the treadle, reciprocates the rubber, which rolls the garment back and forth under the pressure of its weight, which may be regulated as circumstances require. As fast as one part of the fabric is cleansed the laundress moves it along, until the entire fabric has been submitted to the action of the rubber.

The degree of oscillation in the rubber may be varied by moving the yoke to or from the pitman.

I claim as new and desire to secure by Letters Patent—

The construction and arrangement of the frame A, tub B, rub-board K, rubber L, pitman M, yoke N, cranked shafts C and H, pulleys G and J, fly-wheel F, and treadle D, substantially as shown and set forth, for the purposes specified.

DAVID VOGT.
